COMBINATION BABY FORMULA MIXER AND DISPENSER

Isidore Frimerman, New York, N. Y.

Application January 19, 1949, Serial No. 339

Term of patent 14 years

(Cl. D44—21)

To all whom it may concern:

Be it known that I, Isidore Frimerman, a citizen of the United States, residing in the city of New York, in the county of New York and State of New York, have invented a new, original, and ornamental Design for a Combination Baby Formula Mixer and Dispenser, of which the following is a specification, reference being had to the accompanying drawing, forming part thereof.

In the drawing:

Fig. 1 is a side elevational view of a combination baby formula mixer and dispenser, showing my new design;

Fig. 2 is a front elevational view;

Fig. 3 is a rear elevational view; and

Fig. 4 is a top plan view thereof.

I claim:

The ornamental design for a combination baby formula mixer and dispenser, substantially as shown.
